UNITED STATES PATENT OFFICE.

WILLIAM H. HOLMES, OF MOUNT VERNON, NEW YORK.

FILING SYSTEM.

Application filed November 2, 1920. Serial No. 421,258.

To all whom it may concern:

Be it known that I, WILLIAM H. HOLMES, a citizen of the United States, and resident of Mount Vernon, in the county of Westchester and State of New York, have invented a new and Improved Filing System, of which the following is a full, clear, and exact description.

My invention relates to a filing system, and aims to provide an article of this nature which shall embody certain improved constructions over systems and devices of this type heretofore placed upon the market.

It is well appreciated in connection with filing devices commonly termed "systems" that numerous articles of this nature have been presented to the purchasing public, which have embodied the provision of a series of cards arranged one above the other, the lower edges of each being visible and bearing the name to which the data upon the card refers.

These devices, have for the most part presented objectionable features in that primarily, it has been extremely difficult to remove a card from the center of a tier of the same. Second, devices of this nature have been for the most part extremely expensive. Third, numerous limitations have also been found in these systems, in that but one side of the card has been available for recording data, in that the next adjoining cards have been incapable of being moved beyond a limited extent, and fourth, with the invisible filing systems heretofore placed upon the market, the reference data to be associated with the card had necessarily to be limited to the space available for placing data upon the face thereof, no provision being made for the association of any data, such as already filled in cards, etc. with the same.

With these objects in view, I have devised a filing system or device, in which primarily, any card within a tier of cards may be instantaneously removed.

A further object of my invention is the construction of a filing system in which both faces of the card may be available for the writing or inspection of data thereon, when the same are arranged in tier form.

Another object of my invention is the construction of a filing device with which a certain amount of prior data may be attached to

a current card, subject of course to reasonable limitations with regard to the bulk of the same.

Further objects of my invention will appear in the annexed specifications and drawings, which latter present practical embodiments of my invention, and in which—

Figure 1 is a front view of a filing system constructed in accordance with my invention.

Figure 2 is a side view thereof.

Figure 3 is a plan view.

Figure 4 is an enlarged sectional side view of one of the elements forming a part of the same.

Figure 5 is a view similar to Figure 1, but showing a slightly different form of device.

Figure 6 is an enlarged sectional side view taken along the line 6—6 of Figure 5.

Figure 7 is a plan view thereof.

Figure 8 is a perspective view of the upper edge of the device, and showing the cards in their proper position.

Figure 9 is a view similar to Figure 8, but showing one of the cards in the process of removal.

Figure 10 is an enlarged fragmentary sectional side view showing in detail one of the elements of the system illustrated in Figures 5 to 9.

Referring now more particularly to the structure illustrated in Figure 1, it will be seen that I preferably utilize a backing strip 15 provided with inwardly turned side edges 16, to form grooves 17.

It is to be noted that the material from which the backing sheet is constructed is preferably of a flexible nature, so that the body of the same may be distorted, to a certain extent for a purpose hereinafter more fully specified.

Associated with the strip 15 are a series of strips, each including a main body portion 18, which may have its edges 19 bent, so as to impart rigidity to the body 18 to prevent distortion. It is also to be noted that each of the strips is bent adjacent its ends to provide an offset portion 20, adapted to project within the grooves 17 of the backing sheet.

It will also be seen that the offset portion 20 is of such a length, as to permit of the

end of the main body portion of the strip to bear against the free edge of the side edges 16 of the backing sheet, thus providing a frictional engagement between these parts 5 preventing movement of the strip with respect to the backing sheet.

Referring now more particularly to the specific construction of the strip, it will be seen that the same preferably includes a 10 series of lugs, or other suitable securing mediums 21, for rigidly attaching a wire or track 22 to the strip. Slidably mounted upon this track are a series of clasps 23 of any suitable character, by means of which reference cards 24 may be associated one to each of the strips.

It is also to be noted that by virtue of providing preferably more than a pair of 20 clasping members 23 other data 25 extraneous of the card 24 may be also associated with the strip. Thus in the Figures 1 to 4, I have illustrated a filing system or device, which will be extremely simple in construction, and in which each of the cards 24 will be 25 properly retained without any complicated apparatus, each side of each card being available for the association of data therewith, by swinging the card and clasping members 23 around the track or wire 22.

30 To now provide a medium which will permit of the insertion of a card in a position at which the same is interposed between two cards already arranged upon the backing sheet 15, without the necessity of removing 35 these latter cards therefrom, the inwardly turned side edges of the backing sheet 15 are provided with a series of openings 26, which are preferably formed with care, so that a strip may not accidentally ride therethrough.

40 The openings 26 in the opposite side edges are preferably also arranged in staggered relationship one with the other, and by this arrangement, it will be appreciated that by 45 flexing the main strip 15 in the manner specified to permit of a movement of the strips within the groove 17 of the same, that one end of a new strip may be primarily introduced through an opening 26 50 to one of the side walls of the groove 17, and slid within the same to a point at which the opposite end of the strip may be inserted through the next opening of the opposite inturned side edge of the backing sheet.

55 By this arrangement it will be appreciated that it will not be necessary to remove the strips already in position to permit of the introduction of a new strip, and also by arranging the openings 26 of opposite grooves in separate relationship one with the other, that a possibility of one of the strips becoming accidentally dissociated with the backing sheet is precluded.

60 Referring now more particularly to the

construction illustrated in Figures 5 to 10, it will be seen that this construction embraces a backing sheet 27 provided, as in the case of the afore-described figures, with inwardly turned side edges 28, and openings 29 formed through the same.

This construction, however, is particularly adapted for use where a minimum of expense is to be incurred, and with this in view, the strips 30 may be of a simple rectangular form, and of any desirable material. Also, the backing sheet will not necessarily have to embody flexible qualities. As in Figures 1 to 4, a wire or track 31 may be attached to each of the strips 30, and a series of clasping members 32 associated therewith, to provide an attaching medium for the cards 33.

To now provide means which will serve to retain the strips 30 in their proper horizontal plane, it is to be noted that each of the inturned side edges is formed with a series of openings 34 capable of accommodating a detachable button 35, of any suitable character.

It will be obvious that upon the association of the button 35 with the inturned side edge of the backing sheet 27, a certain portion of the button will project into the space 36 existant between the inner face of the main portion of the backing sheet, and inturned side edge thereof, this projecting portion being adapted to engage the lowermost edge of one of the strips 30, to prevent any downward movement on the part of the same.

50 To provide means which will permit of all of the strips being quickly detached from the backing sheet 27, and at the same time to prevent their accidental dissociation with this member, it will be noted, reference being had to Figure 8, that the side portions 37 of the backing sheet 27 are formed with openings 38 adjacent their upper ends, which openings are adapted to receive a retaining strip 39, which latter extends between and firmly seats within the spaces 36, and adjacent the upper end of the same.

55 Thus, reference being had to Figures 5 to 8, it will be seen that any upward motion on the part of the strips 30 is precluded. It will also be apparent that upon the strip 39, which has its end 40 preferably extending beyond the main sheet to provide a grasping portion, being withdrawn, that the strips 30 may readily be removed from the backsheet.

60 Also in the manner described in connection with Figures 1 to 2, new strips may be associated with the backing sheet by the simple expedient of using the openings 29 as aforescribed.

65 From the foregoing it will be noted that by means of my improved construction all of the objects set forth in the preamble of this specification are accomplished, and that

my device will incorporate numerous advantages over devices of this nature heretofore placed upon the market.

Obviously numerous modifications of structure might readily be resorted to without in the least departing from the spirit of my invention, which I claim as—

1. A filing system, including a backing sheet, said backing sheet being formed with 10 grooves adjacent its side edges, one of the side walls of each of said grooves being formed with openings, the openings in opposite grooves being arranged in staggered

relationship one to the other, and strips having ends adapted to pass through said openings and to be received in said grooves.

2. A filing system including a backing strip, said backing strip being formed with grooves adjacent to its side edges, one of the side walls of each of said grooves 20 being formed with openings, strips adapted to have their ends arranged in said grooves, and means adapted to extend through said openings for preventing movement of said strips longitudinally of said grooves.

WILLIAM H. HOLMES.
